METHOD OF OPERATING MERCURY CATHODE CELLS

Joseph L. Wood, Timonium, Md., and Glen P. Henegar, Saltville, Va., assignors to Olin Mathieson Chemical Corporation, a corporation of Virginia
No Drawing. Filed Aug. 25, 1961, Ser. No. 133,790
4 Claims. (Cl. 204—125)

This invention relates to mercury cells for the electrolysis of aqueous solutions of alkali metal compounds, particularly the halides, such as sodium chloride and has for its primary object the provision of a method of operation of a plant made up of a large number of such cells, particularly at the time the plant is started up.

Mercury cell plants comprise a large number of mercury cells and a considerable number of accessory parts. This invention is concerned primarily with a method of installing anodes and starting up a plant consisting of a large number of mercury cells. However, the method is applicable to a relatively small number of cells or even to a single cell having a plurality of anodes.

This invention is concerned particularly with stationary mercury cells which, for a variety of reasons, are relatively long and narrow. Such cells preferably include a conducting bottom with a covering layer of mercury as the cathode, an anode or series of anodes suspended in an electrolysis compartment into the aqueous solution over the layer of mercury. The aqueous solution, for example, a brine of sodium chloride, potassium chloride or lithium chloride and the mercury are introduced at the slightly elevated inlet end. These flow through the compartment to the outlet end while undergoing electrolysis. Chlorine gas is released and an amalgam of the alkali metal is formed. The amalgam is later decomposed in another operation with the formation of hydrogen and, for example, metal hydroxides or alcoholates. The mercury is returned to the cell to repeat the cycle.

The anodes of stationary mercury cells are usually fabricated of rectangular blocks of graphite to each of which is attached a lead-in which provides support for the suspension of the graphite in the aqueous solutions above the mercury cathode. The lead-in also conducts the current from outside the cell, for example, from a bus bar to the graphite anode.

In such cells, high current densities are employed so that it is economical to place the anode close to the mercury cathode. However, graphite anodes tend to erode under the conditions of electrolysis. The lower surfaces of the graphite anode recedes from the mercury cathode, increasing the inter-electrode distance and increasing the voltage required to span the gap through the aqueous brine. In order to maintain high electrical efficiency and low resistance in the cell, it is therefore desirable to adjust the elevation of the anode with respect to the mercury cathode at frequent intervals.

Adjustment of anodes requires an amount of labor which is a material cost in the operation of the cells. Since the rate of erosion of the graphite anodes varies materially, anodes require adjustment and replacement at various times. A fixed labor force can maintain the anodes in adjustment during the operation since the large number of anodes requiring attention averages out the labor requirement for adjustment and replacement.

A problem arises in starting up a new plant in which all of the anodes are new and as uniform as possible. No adjustment or replacement is required for a period of time but after certain elapsed time depending on the graphite, the operating conditions in the cell and other factors, a large proportion of the anodes require adjustment at the same time. Moreover there will be suffi-

2

cient uniformity in erosion that a major proportion of the anodes will require replacement at the same time. These requirements interfere with the smooth operation of the plant and may require the shutdown of a large number of cells at the same time. The operation of the plant is materially improved by the process of the present invention which evens out the schedule for adjustment and replacement of anodes and therefore the labor required is more uniformly spread over a period of time. Furthermore the total operation is more uniform because only a small number of cells are removed from service at any one time for the purpose of anode adjustment or replacement.

The method of the present invention comprises the original installation in a plurality of mercury cells of anodes of varying thickness. After an initial period a considerable proportion of the anodes in the plant require adjustment but replacement of anodes is required only for a small proportion of the anodes at any one time. The required adjustments can be made on a few anodes at a time even though some are less in need of adjustment than others. The major improvement of the process of the present invention is the distribution over a considerable period of time of the greater task of replacing anodes.

In mercury cells the thickness of the anodes initially installed depends on the design of the cell. Ordinarily cells are built with sidewalls capable of accommodating graphite anodes varying in thickness from about 3 to 8 inches or more. It is theoretically most advantageous to install original anodes, no two of which have the same thickness. In this way the maximum leveling of the requirement for replacement is attained. Since this is not feasible in commercial operation, the preferred operation is more practical. The method of the present invention thus comprises the method of producing chlorine and alkali metal amalgam in the electrolytic compartments of mercury cathode cells which comprises suspending in said electrolytic compartments initial graphite anodes having different thicknesses between about 2 and about 8 inches in said electrolytic compartments, supplying aqueous alkali metal brine and mercury to said compartments and electrolyzing the brine to form chlorine gas, depleted brine and alkali metal amalgam. The said initial graphite anodes are subsequently replaced, when worn by electrolysis, by graphite anodes of uniform thickness, preferably anodes of the maximum thickness the design of the cell permits.

For example, in a cell built to accommodate anodes 6 inches thick, it is preferred to install one third of the anodes 3 inches thick, $\frac{1}{3}$ of the anodes 4 inches thick and $\frac{1}{3}$ of the anodes 6 inches thick. The relative proportions of anodes of each thickness may be varied and the specific thicknesses may be varied to utilize graphite blocks commercially available or commercially feasible for this purpose.

It is a particular advantage of the process of the present invention that, in addition to the leveling out of the replacement schedule, unexpected improvements are effected in the operation of the plant particularly with respect to reduced proportions of by-product hydrogen in the chlorine. Deleterious impurities in the brine were reduced and lower hydrogen content in the chlorine was obtained. The graphite from which the anodes are made contained various minor impurities particularly iron, vanadium, and other metals usually present in parts per million. In operation these metals are leached from the graphite rather rapidly. After a period of use the contribution of these minor metallic impurities from the graphite to the brine is greatly reduced. Initially when all the anodes are new and of equal thickness, the brine is substantially contaminated by these metals. When

the thickness of the initial anodes is varied according to the process of the present invention, however, the initial contamination of the brine by metals from the graphite is materially reduced and as a result the hydrogen in the chlorine is maintained at a low level even in the initial stages of operation. As new anodes of uniform thickness are introduced as replacement anodes, the varying thickness of the remaining anodes and their varying age in the cell results in a lower level of metallic contamination in the brine, a chlorine product containing less by-product hydrogen and requiring less of treating agents to remove the contamination in the purification and resaturation of the brine for recycle. Sudden increases in hydrogen content of the chlorine and the chance of explosion due to hydrogen in the chlorine is substantially reduced. In addition, the voltage requirement of each cell is substantially the same as the voltage requirement of every other cell. The resulting power consumption of the plant is thus maintained essentially constant over long periods of time. Overall plant operation efficiency and safety are thus improved.

Example I

In a mercury cell plant comprising 100 stationary cells, each cell requiring 20 anodes, a total of 2,000 anodes are required. In these cells, 600 anodes 3 inches thick, 600 anodes 4 inches thick and 700 anodes 6 inches thick were installed. Anodes of different thicknesses were adjacent to each other so that each cell contained several anodes of each thickness. In the operation of the plant the anodes were adjusted as required from time to time and the anodes were removed and replaced when their thickness averaged about 1 inch. Thus the original 3 inch thick anodes required replacement at the earliest date, the 4 inch thick anodes at an intermediate date and substantially all of the 3- and 4-inch anodes were replaced before it became necessary to replace any of the 6 inch anodes. Anodes, 6 inches thick were used as replacements. After the program of replacement began the requirements were greater at certain times but by the time all the anodes had been replaced, the requirements were uniformly spaced with respect to time.

Example II

In a mercury cell plant of the same number of cells and anodes, as described in Example I, the original installation comprised alternating anodes of 3 inches and 4 inches in thickness. In the operation of the plant the anodes were adjusted as required. When the thickness of each anode was about 1 inch it was replaced with an anode 6 inches thick. The replacement program began about 9 months after startup and continued at a rate which averaged about 10 per day during subsequent operations.

Example III

In a mercury cell plant comprising 50 stationary cells,

each cell required 20 anodes, a total of 1,000 anodes being required. In one-third of these cells, anodes 3 inches thick were installed. In another one-third of the cells, anodes 4 inches thick were installed and in the remaining one-third, anodes 6 inches thick were installed. In each cell the anodes were rotated from end to end of the cell at intervals for more uniform wear. The anodes were removed and replaced when their thickness averaged about 1 inch. The original 3 inch thick anodes were replaced at the earliest date, the 4 inch thick anodes at an intermediate date and substantially all of the 3- and 4-inch anodes were replaced before it became necessary to replace any of the 6-inch anodes. Anodes, 6 inch thick were used as replacements. As each cell was shut down, all the anodes in the cell were replaced. After the program of replacement began the requirements were greater at certain times but by the time all the anodes had been replaced, the requirements were uniformly spaced with respect to time and the power requirement for the entire plant was substantially uniform.

What is claimed is:

1. The method of producing chlorine and alkali metal amalgam in the electrolytic compartments of stationary mercury cathode cells which comprises suspending in said electrolytic compartments initial graphite anodes having different thicknesses between about 2 and about 8 inches, at least one-quarter of said initial anodes having substantially the same thickness, supplying aqueous alkali metal brine and mercury to said compartments and electrolyzing the brine to form chlorine gas, depleted brine and alkali metal amalgam, subsequently replacing said initial graphite anodes by replacement graphite anodes, all of said replacement graphite anodes having substantially the same thickness.
2. The method of claim 1 in which the said initial graphite anodes are subsequently replaced by graphite anodes having the maximum thickness the design of the cell permits.
3. The method of claim 1 in which at least one-quarter but not more than three-quarters of the anodes initially installed have substantially the same thickness and the balance of the anodes have a substantially different thickness.
4. The method of claim 1 in which all the anodes in any one of the said mercury cathode cells have the same thickness and at least one-quarter but not more than three-quarters of the said cells contain anodes of the same thickness.
